UNITED STATES PATENT OFFICE.

JOSEPH BLAEKER, OF NEW YORK, N. Y., ASSIGNOR OF ONE-HALF TO MAXWELL EISENSTEIN, OF NEW YORK, N. Y.

LOCK FOR AUTOMOBILE STEERING WHEELS.

Application filed March 27, 1923, Serial No. 627,952. Renewed October 4, 1926.

Among the principal objects which the present invention has in view are: To prevent tampering with the lock; to add to the strength of the structure thereof; and to provide a relatively simple locking device for automobile steering wheels.

Drawings.

Figure 1 is a front view showing a fragment of steering wheel and tiller-post therefore equipped with a lock constructed and arranged in accordance with the present invention.

Figure 2 is a longitudinal section of the lock taken as on the line 2—2 showing the end of the tiller post and fragment of the wheel.

Figure 3 is a transverse section, the section taken on the line 3—3 in Fig. 2.

Figure 4 is a cross section of the lock, the section being taken on the line 4—4 in Fig. 2.

Figure 5 is a front view showing a fragment of steering wheel and tiller post therefore equipped with a lock constructed and arranged in accordance with a modified form of the invention.

Figure 6 is a vertical cross section of the lock, the section being taken on the line 6—6 in Fig. 7.

Figure 7 is a vertical section of the lock, the section being taken as on the line 7—7 in Fig. 5.

Figure 8 is a horizontal section, the section being taken on the line 8—8 in Figure 7.

Description.

As seen in the drawings, the lock provides a housing in which is slidably fitted a bolt member 10. The member 10 is cut away in its middle section to provide a transverse channel 11, the upper and lower walls 12 of which are preferably parallel or arranged to maintain contact constantly with the periphery of a circular disk 13.

The disk 13 is permanently mounted on the squared portion 14 of the pivot shaft 15. The shaft 15 has the reduced pivot end 16 for which a bearing is provided in the housing 9 as best seen in Figures 2 and 4 of the drawings. The opposite end of the shaft 15 is shaped to provide a socket 17 wherein the extension 18 of the key barrel is inserted. As can be best seen in Fig. 2 of the drawings, the key barrel has a key-way 19. The tumblers 20 of the lock are arranged and oper-

ated in the manner usual to locks of this description. The lock 21 is mounted in a hollow boss 22 which is tapped to receive the threads with which such locks 21 are generally provided.

The housing 9 has a bracket 23 which forms in conjunction with the cap 24 a clamp for holding the lock firmly in position on the tiller post 25. It will be understood that though I have shown no means for pinning the bracket or collar on the tiller post this may be accomplished in the manner usual to such constructions without varying from the spirit of the present invention.

The bolt member 10 is moved by the disk 13 to and from the positions indicated by full lines and dotted lines in Fig. 3 of the drawings, and in accordance with the movement of the said disk. The path of the disk is indicated in Fig. 3.

From the fact that the disk 13 is circular and that the opposite sides of the periphery thereof is always in contact with the opposite walls 12 of the channel 11, it is obvious that in whatever position the disk 13 is left by the operator, it offers a full and complete resistance to the movement of the member 10, either upward or downward.

The upper end of the bolt 10 is bifurcated to provide a yoke, the horns 27 whereof are designed to engage one of the spokes 28 with which the wheel 29 is provided when the said spoke is moved into position directly in line with the member 10 and the horns 27.

To operate the present invention, a key is placed in the key-way 19 of the lock 21 when the member 10 is disposed in its raised position as shown in the drawings. When the key and key barrel connected therewith are rotated, the disk 13 is gyrated until it assumes a position shown by broken lines in Fig. 3 of the drawings. In this position of the disk 13 the member 10 will be lowered to the position shown by broken lines in said Figure 3, and the key will be held in the said key-way 19. The horns 27 of the yoke will be lowered out of the path of the spokes 28 of the wheel 29. The said wheel and the steering mechanism connected therewith are thereafter free to move.

When now the operator desires to lock the car against interference, he places the wheel 29 in position where one of the spokes 28 are alined with the member 10 and the horns 27 thereof. The key is then rotated to

place the disk in the position shown by the full lines in Figures 2 and 3.

By doing this the driver has placed the member 10 in position to hold the steering wheel 29 from operation and the disk 13 from movement.

As long as the disk 13 is in the position shown by full lines in Figures 2 and 3, it is obvious that no amount of vibration can dislodge the said disk and the member 10 supported thereby.

The modification shown in Figures 5 to 8 inclusive consists principally in that the bolt member 30 is circular in cross section and the housing 31 is also circular forming a hollow box through which the pivot shaft 15 extends. In all other essentials the lock shown in Figures 5 to 8 are the same in principle and function as those disclosed in Figures 1 to 4 inclusive.

Claims.

1. A lock as characterized comprising the combination with a housing having a vertical open-ended channel; of a bolt member slidably mounted in said housing, said member having a transverse channel; a lock rotatively mounted in said housing and having a circular disk-like member mounted in line with the key barrel of said lock and in eccentric relation thereto, the diameter of said disk being equal to the distance between opposite walls of the channel of said bolt member; and means for rotating said disk.
2. A lock as characterized comprising the combination with a housing having a vertical open-ended channel; of a bolt member slidably mounted in said housing, said member having a transverse channel; a lock rotatively mounted in said housing and having a circular disk-like member mounted in line with the key barrel of said lock and in eccentric relation thereto, the diameter of said disk being equal to the distance between opposite walls of the channel of said bolt member; and a removable key for insertion within said lock to operate the same.
3. A lock as characterized comprising the combination with a housing having a vertical open-ended channel; of a bolt member slidably mounted in said housing, said member having a transverse channel; a lock rotatively mounted in said housing and having a circular disk-like member mounted in line with the key barrel of said lock and in eccentric relation thereto, the diameter of said disk being equal to the distance between opposite walls of the channel of said bolt member; a removable key for insertion within

said lock to operate the same; and a clamp rigidly connected with said housing for maintaining the position of the same on the tiller post of a vehicle.

4. A lock as characterized comprising the combination with a housing having a vertical open-ended channel; of a bolt member slidably mounted in said housing, said member having a transverse channel; a lock rotatively mounted in said housing and having a circular disk-like member mounted in line with the key barrel of said lock and in eccentric relation thereto, the diameter of said disk being equal to the distance between opposite walls of the channel of said bolt member; a removable key for insertion within said lock to operate the same; and a clamp rigidly connected with the said housing for maintaining the position of the same on the tiller post of a vehicle, said clamp having a bracket integrally formed on said housing and a removable clamp cap rigidly and permanently secured thereto.

5. A lock as characterized comprising the combination with a bolt member having a bifurcated end and a transverse channel; of a housing adapted to be rigidly and permanently mounted on the tiller post of the steering apparatus of a vehicle, and an eccentrically mounted disk member rotatively mounted in said housing to rest in said channel; and means for rotating said disk.

6. A lock as characterized comprising the combination with a bolt member having a bifurcated end and a transverse channel; of a housing adapted to be rigidly and permanently mounted on the tiller post of the steering apparatus of a vehicle, and an eccentrically mounted disk member rotatively mounted in said housing to rest in said channel; and means for rotating the same, said means embodying a key operated member.

7. A lock as characterized comprising the combination with a housing adapted to be secured on a tiller post and provided with a vertical open ended channel therethrough, of a bolt member slidably mounted for vertical movement in said channel and having a transverse channel formed intermediate its ends at a point within said housing, a lock barrel rotatably mounted in said housing, a cam disposed in the channel of said bolt member and connected for operation to said lock barrel, and a key for operating said barrel to raise and lower said bolt member for locking engagement with a spoke of a steering wheel.

JOSEPH BLAEKER.
